(57) **CLAIM**

The ornamental design for a protective housing for an electrical cable connection, as shown and described.

DESCRIPTION

FIG. 1 is a top perspective view from the left of the protective housing for an electrical cable connection; FIG. 2 is a top perspective view from the right of the design; FIG. 3 is a bottom perspective view from the left of the design;

FIG. 4 is a bottom perspective view from the right of the design;

FIG. 5 is a front view of the design;

FIG. 6 is a rear view of the design;

FIG. 7 is a left side view of the design;

FIG. 8 is a right side view of the design;

FIG. 9 is a top view of the design; and,

FIG. 10 is a bottom view of the design.

The broken lines in the Figures are for the purpose of illustrating portions of the protective housing for an electrical cable that form no part of the claimed design.
